UNITED STATES PATENT OFFICE.

JOHN PHELAN, OF PITTSBURG, PENNSYLVANIA; NICHOLAS A. PHELAN ADMINISTRATOR OF SAID JOHN PHELAN, DECEASED.

DEVICE FOR SECURING RAILWAY-RAILS TO METALLIC TIES.

No. 921,277.

Specification of Letters Patent.

Patented May 11, 1909.

Application filed October 21, 1907. Serial No. 398,353.

To all whom it may concern:

Be it known that I, JOHN PHELAN, of Pittsburgh, in the county of Allegheny, State of Pennsylvania, have invented a certain new and useful Improvement in Devices for Securing Railway-Rails to Metallic Ties, of which the following is a full, clear, and exact description, reference being had to the accompanying drawing, forming part of this specification, in which—

Figure 1 is a side elevation of a metallic tie showing my improvement applied thereto; Fig. 2 is an end elevation partly in section; Fig. 3 is a perspective view of the securing clip; Fig. 4 is a vertical sectional view showing the angularly disposed holes in the top flange of the tie.

My invention relates to devices for securing railway rails to metallic ties, and I have shown it applied to a metallic tie of the ordinary I-beam construction, although it may be applied in a like manner to other metallic ties; and it consists of a securing clip having depending parallel shanks adapted to be driven through angularly disposed openings in the upper face of the tie, whereby said shanks are caused to be spread apart, forming an effective clench, and a perfectly tight and secure fastening for the rail is formed.

In the drawing A represents a metallic tie of the ordinary I-beam type, having a top flange 2, a bottom flange 3, and a connecting web 4. Formed in the flange 2, at suitable points at each side of the base of the rail are the diverging or oppositely inclined openings 5.

The securing device B, which may be made of any suitable metal such as steel or wrought iron, consists of a head 6 having a laterally projecting lip 6', and two depending parallel shanks 7 and 7'. When in use, the shanks 7 and 7' are driven through the angularly disposed openings 5, which causes the shanks to diverge or separate until the lip 6' engages the base flange of the rail. Thus the securing device is automatically locked by the mere

driving of the securing device downward and a firm and rigid clench is formed between the rail and the tie.

The angularly disposed apertures 5 serve an important function, as they cause the shanks 7 and 7' to be spread apart, whereby considerable resistance and holding power is attained, and the securing device is not liable to become loose or work out under the vibration of the rails caused by the passing train.

Although I have shown one form of securing clip, I do not desire to limit myself thereto, as various changes may be made without departing from the spirit of my invention, nor do I desire to limit myself to the use of one clip on each side of the rail, as the number may be increased if desired where space permits.

Having thus described my invention, what I claim and desire to secure by Letters Patent is:

1. The combination with a metallic railway tie having oppositely inclined openings in the top wall thereof, of a securing device having a laterally projecting lip adapted to engage the base flange of a railway rail, and depending shanks adapted, when driven through the openings in the tie, to separate or diverge; substantially as shown and described.

2. The combination with a metallic railway tie having diverging or oppositely inclined openings formed in the top wall thereof, of a securing device having an overhanging lip portion adapted to engage with the base flange of a railway rail, and depending shanks adapted to spread when driven through the said openings in the tie; substantially as shown and described.

In testimony whereof, I have hereunto set my hand.

JOHN PHELAN.
